CLAIM

We claim the ornamental design for a vehicular front chin splitter, as shown and described.

DESCRIPTION

FIG. 1 is a front perspective view of a vehicular front chin splitter, of the new design;

FIG. 2 is a rear perspective view thereof;

FIG. 3 is a front view thereof;

FIG. 4 is a rear view thereof;

FIG. 5 is a side view thereof;

FIG. 6 is a side view thereof, opposite that of FIG. 5;

FIG. 7 is a top view thereof; and,

FIG. 8 is a bottom view thereof.

1 Claim, 6 Drawing Sheets
